UNITED STATES PATENT OFFICE.

CHARLIE L. KUBISTA, OF SLEEPY EYE, MINNESOTA.

CLOTHESLINE HOLDER.

Application filed December 26, 1922. Serial No. 608,983.

This invention relates to new and useful improvements in clothes-line holders such as are commonly used to support a clothes-line for the purpose of hanging clothes, etc., thereon, and relates more particularly to such holders adapted to contain and conceal the line therein when not in use.

The novel clothes-line holder illustrated in the accompanying drawings is designed with a hollow standard or post which may be anchored in any suitable manner, such as by sinking in the ground. When the clothes-line is not in use it will be concealed within the hollow standard in such a manner as to be positively protected against dust and weather, thus eliminating the usual objection of having to put up and take down the line after each washing.

Means are also provided whereby the line may be readily and quickly withdrawn from the holder and secured to any suitable means such as the cross-arm of an ordinary clothes pole. The line is also preferably constructed in one piece being retained in the hollow standard by means of a suitable weight and a plurality of grooved pulleys. The ends of the line are preferably secured to each other adjacent a cover plate or hand-grip closing the opening in the standard through which the line is drawn. The line then passes over the pulleys, back to the cover plate and again back to the pulleys thereby providing means for equalizing the tension of the line sections when withdrawn from the standard. The line may be used either as a single line or it may be arranged in such a manner as to provide a plurality of lines.

This holder is also provided with means for spreading the line sections and also with means for preventing the line from becoming loose or slack when carrying heavy articles, such as carpets, clothing, etc.

Another important feature of this novel clothes line holder resides in its simple and inexpensive construction, thus providing a holder which may be manufactured at a minimum cost.

The object therefore of this invention is to provide an improved clothes-line holder.

Other objects of the invention will more fully appear from the following detailed description and the accompanying drawings and will be pointed out in the annexed claims.

In the drawings, there has been disclosed a structure designed to carry out the objects of the invention but it is to be understood that the invention is not confined to the exact features shown, as various changes may be made within the scope of the claims which follow.

In the drawings:

Figure 1 is a vertical sectional view of a clothes-line holder showing the invention applied thereto, and also showing the line concealed within the post;

Figure 2 is a view in front elevation of the upper end of the holder, showing the line partially withdrawn therefrom;

Figure 3 is a cross-sectional view on the irregular line 3—3 of Figure 1;

Figure 4 is a detail vertical sectional view on the line 4—4 of Figure 1, showing the upper grooved drum or pulley in position;

Figure 5 is a detail vertical sectional view on the line 5—5 of Figure 1, showing the grooved pulleys provided in the upper end of the weight;

Figure 6 is a detail view of the top of the post, showing the manner of mounting the upper grooved pulley or drum in the cap;

Figure 7 is a diagrammatic view showing the method of threading the line upon the pulleys;

Figure 8 is a vertical sectional view on the line 8—8 of Figure 7;

Figure 9 is a detail view of the upper end of the post with the cap removed.

In the selected embodiment of the invention shown in the accompanying drawings there is illustrated a clothes-line holder comprising a hollow post 15 preferably polygonal in cross-section and having a bottom plate 16 and top cap 17. The bottom plate 16 may be secured to the post by any suitable means whereby a waterproof joint may be provided between the wall of the post and the upturned flange 18 of the plate, thus preventing water and moisture from entering the post from the bottom.

The clothes-line is adapted normally to be held in yieldably retracted position within the post wherein it is operatively passed about a plurality of pulleys. Two sets of pulleys are provided, the upper being held about a relatively fixed axis while the lower set is movably carried by the line sections in suspended position. While the upper set

2
may consist of a plurality of separate pulleys, it is preferred to employ a single upper pulley with several line grooves. Referring to Figure 1 it will be noted that a 5 grooved drum or pulley 19 is provided at the upper end of the post. This pulley is mounted upon a suitable rod or rivet 21, preferably secured to the depending flange 22 of the top cap 17. (Figure 6.) Opposed 10 vertical slots 23 are provided at the upper end of the post 15 adapted to receive the rod 21 when the cap is placed thereon.

A suitable opening 24 is also provided at the upper end of the post adjacent the lower 15 edge of the flange 22 of the cover through which the line passes when withdrawn from the holder, as shown in Figure 2. This opening is provided with inwardly projecting upper and lower horizontal flanges 25 and 20 26 adapted to have suitable guide pins 27 secured thereto. (Figures 1 and 3.) These pins function in separating the outer line sections as they pass out and in through the opening 24. A horizontal rod 28 is 25 mounted at the upper end of the hollow post 15 adjacent the lower flange 26 and is arranged at substantially right angles with 30 reference to the openings 24. This rod functions as a means for separating the center line sections.

Means are provided for spreading the lines, when desired.

An arched metallic spreader frame 29 is 35 pivotally mounted in the upper portion of the post 15 as by means of a suitable bolt 31. This bolt passes transversely through the post slightly to one side of its vertical axis and substantially in alignment with the center of the opening 24, so that it also may 40 function as a means for guiding the line sections through the opening when retracted from the post. The frame 29 is provided with opposed outwardly extending arms 32 (Figure 2) which are provided with 45 suitable notches 33 adapted to receive the line sections (as indicated in Figures 1, 2 and 3) when it is desired to spread the lines. A suitable arched cross member 34 has each 50 end secured to the frame 29, adjacent the arm 32, to provide a supporting means between the two side members of the frame. When this pivoted spreader is in line-engaging 55 operative position, it not only prevents tilting of the spaced lines when unequally loaded, but it also may rock more or less with the lines, and when the out line-ends are released, the spreader will automatically drop so that the line sections may be freed 60 from the angled notches.

Means are also provided whereby the line will be automatically returned to the post as soon as the user releases the end which has been withdrawn therefrom. This is 65 preferably effected by gravity acting through a weight such as a receptacle 35,

having a bottom plate 36, and adapted for reciprocal movement within the post 15. This receptacle is preferably filled with a suitable ballast of sufficient weight to return the line to the post when released, and 70 at the same time to permit the user readily and quickly to withdraw the line therefrom when it is desired to use it.

The clothes-line is carried by a system of 75 pulleys within the post. The lower group of grooved pulleys 37, 38 and 39 are rotatably mounted upon a suitable rod 41 having its ends secured to the walls of the weight receptacle adjacent its upper edge. A guard 42 is secured to the receptacle by means of 80 upwardly extending ends 43 interposed between the ends of the pulleys 37 and 39 and the walls of the receptacle 35. These upwardly extending ends are apertured to receive the rod 41. It will also be noted, 85 see Figure 5, that the upper terminal edges of the ends 43 are preferably bent outwardly at substantially right angles to the ends 43 and adapted to fit over the upper edge of the receptacle 35, thereby providing 90 means for preventing the guard 42 from changing its relative position with reference to the rod 41.

The opening 24 of the post is adapted to 95 be closed by means of a cover plate 46 so that dust, dirt and the elements may be excluded from the hollow post when the line is in retracted inoperative position. Preferably a single clothes-line 44 is used and the two ends are adapted to be tied together 100 preferably after passing through the oppositely spaced eyes 45 and 47 projecting from the inner face of the coverplate while an intermediate and similarly projecting eye 48 may have an intermediate portion of the line 105 slidably passed therethrough. A ring 49 projects from the outer face of the coverplate and presents means by which the user 110 may withdraw the plate and line from the post.

When the coverplate is withdrawn, the line is also withdrawn and it is so threaded or passed about the pulley system that four line sections are presented.

The method of threading the line upon 115 the lower pulleys and the upper pulley 19 may be explained with reference to Figures 2, 7 and 8. From the loop 45 the line 44 passes rearwardly through the post-opening 24, over the bolt 31 between one of the vertical guide pins 27 and the wall of the post, 120 (Figure 2) thence downwardly to the pulley 39 and rearwardly within its groove 58 and thence upwardly to the groove 59 of the pulley 19. Coming forwardly in this groove 125 59, the line passes downwardly to the groove 61 of the pulley 38 and rearwardly therein and upwardly, over the front side of the upper pulley 19 in the groove 62, thence rearwardly and downwardly again to the pul- 130

ley 39 and forwardly in its other groove 63 and again upwardly over the rod 31, between the guide pins 27, and out through the opening 24 to the eye 48 in the cover-
5 plate 46.

The line then continues through the eye 48, back through the opening 24 between the guide pins 27, and over the rod 31. From there it extends downwardly and is
10 received in the groove 64 of the pulley 37. It passes rearwardly around this pulley groove, thence upwardly and forwardly in the groove 65 provided in the pulley 19 and then downwardly to the groove 66 in
15 the pulley 38, entering this groove also from the back side. From the groove 66 the line passes to the groove 67 in the upper pulley, around this pulley and down the back side thereof to the groove 68 provided in the
20 pulley 37. The line enters this groove from the back side of the pulley 37 then extends upwardly and over the rod 31, between one of the guide pins 27 and the wall of the post, and is terminally passed through the
25 eye 47 carried by the coverplate 46 and secured to the other end.

The clothes-line, when tautly drawn outwardly, will automatically adjust itself upon the pulleys so that the various line sections
30 will have substantially equal tension. This equalizing action is effected by securing the two ends of the line together and slidably mounting the line in the eyes 45 and 47 of the coverplate by permitting the intermediate line portion freely to slide in the eye 48, and by permitting the central double-grooved lower pulley 38 to revolve independently of the other two lower pulleys. It may be noted that the middle pulley 38
35 does not normally revolve during withdrawal or retraction of the line but does revolve when uneven line tensions are being automatically equalized.

Having thus described my invention, what
40 I claim as new and desire to secure by Letters Patent, is:

1. A clothes-line holder including a post having an aperture, means carried by said post and adapted to have the line passed thereabout to permit withdrawal and extension of the line through said aperture to object-supporting position, tension means normally to hold the line in retracted inoperative position, a detachable cover for said aperture adapted to have one portion of the line secured thereto, and means on said cover slidably to engage another portion of the line whereby upon withdrawal of the cover a plurality of line sections are presented for support of objects.
45

2. A clothes-line holder including a post, pulleys carried by said post and adapted to have the line passed thereabout to permit withdrawal and extension of the line to object-supporting position, tension means nor-
50

mally to hold the line in retracted inoperative position, a handle member adapted to have one portion of the line secured thereto, means on said handle slidably to engage another portion of the line whereby upon withdrawal of the handle a plurality of line sections are presented for support of objects, and means to equalize the tension upon the withdrawn sections.
55

3. A clothes-line holder including a hollow post, pulleys carried within the post and adapted to have the line passed thereabout to permit withdrawal and extension of the line to object-supporting position, means normally to hold the line in retracted inoperative position, the post having an opening adjacent its upper end through which the line may be withdrawn and retracted, a cover for the opening, means on the cover slidably to engage a plurality of portions of the line whereby upon removal of the cover a plurality of line sections are presented for support of objects.
60

4. A clothes-line holder including a post, means carried by the post and adapted to have the line passed thereabout to permit withdrawal and extension of the line to object-supporting position, means normally to hold the line in retracted inoperative position, a handle member adapted to have one portion of the line secured thereto, means on the handle slidably to engage another portion of the line whereby upon withdrawal of the handle a plurality of line sections are presented for support of objects, and means to guide the line sections upon withdrawal and retraction.
65

5. A clothes-line holder including a post, pulleys carried by the post and adapted to have the line passed thereabout to permit withdrawal and extension of the line to object-supporting position, a handle member having eyes through which portions of the line are adapted to be secured whereby upon withdrawal of the handle a plurality of line sections are presented for support of objects, line-guiding elements horizontally and vertically carried by the post whereby upon withdrawal of the handle the line sections are guided substantially in spaced relation.
70

6. A clothes-line holder including a post, pulleys carried by the post and adapted to have the line passed thereabout to permit the line to present upon withdrawal a plurality of line-sections, and a spreader movably mounted on said post and adapted to be operatively positioned to engage the withdrawn line sections to hold the same in spaced relation.
75

7. A clothes-line holder including a post, pulleys carried by the post and adapted to have the line passed thereabout to permit the line to present upon withdrawal a plurality of line-sections, arms pivotally mounted on the post and oppositely extending
80

therefrom, and means on said arms adapted to engage the withdrawn line sections to hold the same in spaced relation.

8. A clothes-line holder including a low post, upper and lower pulley members carried in spaced relation within the post and adapted to have the line passed thereabout to permit withdrawal and extension of the line to object-supporting position, a cap

for the post, a pivot element for the upper pulley member carried by the cap, the upper end of the post having opposed slots to receive said pivot element when the cap is in seated position.

In witness whereof, I have hereunto set my hand this 15th day of December 1922.

CHARLIE L. KUBISTA.
